(57) **CLAIM**

The ornamental design for a seat cover holder, as shown and described.

DESCRIPTION

FIG. 1 is a perspective view of the ornamental design for a wall dispenser of the invention.

FIG. 2 is a front elevational view thereof.

FIG. 3 is a rear elevational view thereof.

FIG. 4 is a left side elevational view thereof, the right side being a mirror image thereof; and,

FIG. 5 is a bottom plan view thereof.

The fragmentary broken-line disclosure of a seat cover shown the drawings is for illustrative purposes only and forms no part of the claimed design.
